OIL RESERVOIR ALARM FOR COOK STOVES

Filed April 23, 1927

2 Sheets-Sheet 2

UNITED STATES PATENT OFFICE.

JOSEPH H. ALLEN, OF CHANDLER, ARIZONA.

OIL-RESERVOIR ALARM FOR COOK STOVES.

Application filed April 23, 1927. Serial No. 186,150.

This invention relates to signals or alarms for indicating a low level of liquid in a container or reservoir and particularly to means for this purpose adapted to be disposed in connection with the oil bowl of an oil stove which will indicate when the oil level has sunk in the bowl below a predetermined amount, so as to warn the housewife that the container should be refilled.

Another object is to provide a device of this character which will only operate when the oil level has sunken so that there is very little oil left in the bowl beneath the reservoir.

A further object is to provide a device of this character having a bell and a clapper, the clapper being held in a raised position by float operated means so that when the float sinks below a predetermined level, the clapper will be released and will strike the bell.

Other objects have to do with the details of construction and arrangement of parts as will appear more fully hereinafter.

My invention is illustrated in the accompanying drawings, wherein:—

Figure 1 is a sectional view of the bowl of an oil stove with my attachment applied thereto, the view showing the reservoir container inverted upon the bowl;

Fig. 2 is a like view to Figure 1 but showing the clapper released;

Fig. 3 is a fragmentary top plan view of the attachment, the wall of the bowl being in section;

Fig. 4 is a sectional view on the line 4—4 of Figure 1;

Fig. 5 is a sectional view of the bell and its support;

Fig. 6 is a view of the support for the alarm;

Fig. 7 is an elevation of the clapper;

Fig. 8 is a plan view of the washer 24.

Referring to these drawings it will be seen that the alarm mechanism is mounted upon a frame designated generally 10, which is preferably formed of wire, the wire being bent to provide an elongated U-shaped member and provide a longitudinally extending slot 11 and the two legs 12 which, at their upper ends, are divergently bent and formed with eyes 13.

Mounted upon the legs 12 midway of the length of the frame, is a base plate 14, the ends of which embrace the legs 12, this plate being formed with a longitudinally extend-

ing slot 15. Mounted upon the plate 14 is the U-shaped member 16 providing outwardly projecting ears having indentations 17. This constitutes the clapper support and is mounted upon the plate 14 by means of the bolt 18 and nut 19, the bolt passing through the slot 15.

The clapper, as shown in Figure 7, consists of a head 20 having resilient legs 21 angularly bent at their extremities and pointed so as to enter into the indentures or holes 17. The bell 22 is provided with a bolt or screw 23 upon which are mounted the clamping nuts 24. These are formed so as to engage the legs which define the slot 11 and thus clamp the bell to the frame 10. The bell is adjustable along the slot 11 and the clapper is adjustable longitudinally of the base plate 14.

Mounted on ears 25 projecting inward from the bowl or base 26 is a float lever 27 which is pivoted upon trunnions 28 and extends out through the bowl and has serrations 29 on its under edge face which engage with a tooth 30 formed upon the extremity of the head 20 when the clapper is raised.

To the other end of the lever 27 is attached a float 31 of any suitable character. The buoyancy of this float causes the outer end of the lever 27 to be depressed, thus holding the clapper in its raised position but when the oil has been nearly entirely discharged from the bowl 26, the float will sink and the serrations will be lifted

from engagement with the tooth 30 and the clapper will swing downward and strike the bell 22. The adjustments for the clapper and the adjustments for the bell are provided so that the clapper and bell may be sure to engage with each other when the clapper falls, and furthermore the indentations 17 permit the pivotal end of the clapper to be adjusted inward or outward.

Preferably the ears 25 have screw-threaded shanks which may pass through the side walls of the wall of the bowl, the wall of the bowl being engaged by the nuts 32. I do not wish to be limited to this nor the exact form of the frame 10 as the form of the frame and the size of the frame will be varied depending upon the particular form of the bowl.

The metal bowls used in connection with inverted tanks or containers such as the container A shown in Fig. 1 differ somewhat in size and shape with different makes of

stoves. The particular form of bowl illustrated in my drawings is one wherein the bowl is somewhat flared at the top and smaller in diameter than the tank or reservoir which simply rests upon its upper edge in inverted position, the tank being supported in the center by a loop extending from the stove. In other forms of oil stoves, however, the bowl is larger and deeper and the tank or container when inverted is telescoped into the bowl. In my invention when the oil is out of the tank and begins to recede in the bowl, then when the oil reaches a proper point of recession, any further recession of the oil releases the clapper and the signal is given while there is still enough oil left to keep the stove burning for fifteen to thirty minutes according to the number of burners being used. The clapper shank can be adjusted so as to permit a greater or less lowering of the oil before the clapper is released. The lower portion of the supporting frame of the clapper does not need to fit snugly against the bottom of the bowl and if the bowl is of such shape that the clapper will not strike it when the frame is resting against the bottom the frame can be slightly bent or otherwise adjusted so as to suit the clapper regardless of the particular shape of the bottom of the bowl.

Obviously many changes might be made in the details of construction and arrangement of parts illustrated without departing from the spirit of the invention as defined in the appended claims.

I claim:

1. The combination with a bowl, of a lever mounted upon the bowl, a float engaging the lower end of the lever, the outer end of the lever being formed with serrations, a bell clapper normally held in an inoperative position by said serrations but released upon the fall of the float, and a bell with which the clapper engages when it falls.

2. The combination with the bowl of an oil stove reservoir, of a low level alarm including a float, a lever extending upward from the float and then outward through the wall of the bowl, said lever being pivoted upon the bowl wall, the outer end of the lever being serrated, a clapper pivotally supported in conjunction with the bowl and having a tooth adapted to be engaged by said serrations to hold the clapper in a raised position, and a bell with which the clapper engages when it is released.

3. The combination with the bowl of an oil stove reservoir, of a frame disposed upon the exterior of the bowl, a bell supported by the frame, a clapper pivotally supported by the frame, a lever mounted upon the wall of

the bowl and having a portion extending through the wall of the bowl and serrated to engage said clapper and hold the clapper raised, the inner end of the lever being extended downward toward the bottom of the reservoir and being provided with a float.

4. The combination with the bowl of an oil stove reservoir, of a frame disposed upon the exterior of the bowl, a bell supported by the frame, a clapper pivotally supported by the frame, a lever mounted upon the wall of the bowl and having a portion extending through the wall of the bowl and serrated to engage said clapper and hold the clapper raised, the inner end of the lever being extended downward toward the bottom of the bowl and being provided with a float, the frame having means whereby the pivotal center of the clapper may be adjusted and whereby the bell may be adjusted toward or from the clapper.

5. The combination with the bowl of an oil stove reservoir, of a low level alarm therefor comprising a curved frame adapted to approximately fit the bottom of the bowl, a bell adjustably supported upon the lower end of the frame, ears adjustably supported upon the middle of the frame, a clapper pivotally and adjustably supported upon said ears and adapted to strike the bell as the clapper swings downward, and means for holding the clapper in a raised position including a lever pivoted upon the inside of the bowl and having one arm extended therethrough and formed with serrations to engage the clapper, the inner arm of the lever being extended downward toward the bottom of the bowl and being provided with a float.

6. The combination with a bowl of an oil stove reservoir, of a low level alarm including an annular float adapted to receive the contracted neck of the oil tank, a lever mounted upon the bowl, the float engaged with the lower end of the lever, a bell clapper coacting with the bowl and means whereby the lever is operatively engaged with the clapper to hold the lever in an inoperative position when the float is raised by the liquid, but releasing the clapper when the float descends.

7. The combination with a bowl, of a lever mounted upon the bowl, a float engaging the lower end of the lever, the outer end of the lever being formed with a detent, a signal actuating member normally held in an inoperative position by said detent but released from the fall of the float, and a signal operated by the fall of said member.

In testimony whereof I hereunto affix my signature.

JOSEPH H. ALLEN.
